WELT HOLDING MECHANISM

William C. Card, Jr., Winthrop, Mass., assignor
to Compo Shoe Machinery Corporation, New
York, N. Y., a corporation of Delaware

Application October 19, 1934, Serial No. 748,981

17 Claims. (Cl. 12—33)

This invention relates to the manufacture of shoes, and more particularly to an apparatus for holding down the welt extension of a shoe when pressure is applied to its bottom, as during a channel laying, sole conforming or sole affixing operation.

A general object of the invention is to provide an improved welt hold-down apparatus to be used in conjunction with pressure applying devices such as sole presses and the like.

More particularly the invention has for its objects the provision of a welt hold-down device which is in the form of a unit readily attachable to existing forms of shoe presses, is easy to operate and control, readily adjustable, compact and relatively simple and inexpensive in structure, and in general is highly practical and satisfactory in operation.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Fig. 1 is a plan view of a shoe press equipped with one form of a welt hold-down device constructed in accordance with the principles of the present invention, part of the upper portion of the press being broken away more clearly to illustrate the welt hold-down structure;

Fig. 2 is a side elevation of the press shown in Fig. 1, parts thereof being shown in longitudinal sections corresponding to line 2—2 of that figure;

Fig. 3 is a horizontal sectional view, substantially corresponding to line 3—3 of Fig. 2 but showing the welt hold-down equipment in open position;

Fig. 4 is a transverse vertical sectional view across a shoe press, substantially corresponding to line 4—4 of Fig. 3;

Fig. 5 is a plan view of a press equipped with another form of welt hold-down device, the upper portion thereof being broken away along line 5—5 of Fig. 6 better to illustrate the welt hold-down construction;

Fig. 6 is a side elevation of the press shown in Fig. 5, parts thereof being broken away substantially along line 6—6 of that figure; and

Fig. 7 is a transverse vertical sectional view, taken substantially along line 7—7 of Fig. 5.

A very satisfactory type of cemented shoe can be made by following the lasting operations customarily used in the manufacture of sewed welt shoes up until the time of applying the outer sole, which latter then is cemented to the welt on the upper instead of being stitched thereto. Such cement affixing operation is accomplished in an inflatable press of the kind customarily used in the application of outer soles to cemented shoes. When pressure is thus applied to the bottom of the outer sole, it is desirable that some means of support be given the welt extension which projects beyond the body of the upper in order to prevent this extension from being rolled or curved by the pressure pad and also to assure firm cement adhesion between such extension and the outer sole. Such a supporting means also is desirable in sole affixing ordinary cemented shoes which are not equipped with a welt in order to prevent rolling of the sole extension.

In sole conforming operations, and in channel laying operations on sewed shoes, it is also desirable to support the welt extension against pressure applied to the bottom of the outer sole.

The present device is intended to provide such a welt extension supporting means and is useful in any operation such as those mentioned. Accordingly, while for convenience of reference, terms such as "welt extension" and "welt crease" are used in the present description and claims, it is intended that these terms shall, wherever the context permits, refer to the marginal portion of an extension edge of the outer sole, regardless of whether or not the shoe is of the welt type.

Referring more particularly to the drawings, there is shown a shoe press having a base portion 10 and a rigid bow member 11 from which extend a toe post 12 and a heel post 13. An inflatable pressure applying pad 14 is positioned in the base portion 10 and is adapted to be blown up and inflated in any suitable manner in order to apply pressure to the bottom of a shoe seated thereon.

In the form here illustrated, the toe post 12 has a threaded shank, the upper portion of which is screwed into the bow member 11, its vertical position with respect thereto being determined by a lock nut 15. A welt hold-down device is mounted as a unit on the downwardly projecting portion of this toe post.

Such device includes a collar or sleeve 16 which is threaded over the toe post and has its vertical

location thereon determined by a lock nut 17. A support 18 is swingably suspended from collar 16 by means of threaded trunnions 19 and 20 which are insertable through laterally extending threaded openings in an upwardly projecting boss 21 of support 18. By virtue of this suspension, support 18 is able to rock forwardly and rearwardly about an axis extending transversely of the press.

10 The support has a forwardly projecting tongue 22 having a longitudinally extending elongate slot 23. The support is further equipped with laterally extending wings 24 and 25, which have elongate slots 26 and 27. The slots 27 extend generally in a longitudinal direction and are roughly of segmental or triangular shape, each having its narrower end disposed rearwardly. A pair of aligned arms 28 and 29 are respectively disposed above and below the slot 27 of wing 25 and are 15 pivoted to such wing adjacent its narrow end by means of a pivot pin 30. The arms 28 and 29 thus are able to swing across the segmentally shaped slot 27. Each of the arms 28 and 29 is equipped with an elongate slot such as 31, these 20 slots being in substantial vertical registry.

25 A similar pair of arms 32 and 33 are respectively located above and below the slot 26 of support wing 24 and are swingable thereacross by virtue of a pivot 34 located adjacent the narrow end of such slot. Arms 32 and 33 each have an elongate slot 35, the slots in the two arms being in substantial vertical registry.

30 A post 36 extends slidably through the forward slot 23 of the support 18 and terminates at its lower end in a pivot pin portion 37 on which are pivotally mounted the forward ends of a pair of welt crease engaging platens 38 and 39. These platens are mutually configured to extend within the welt crease around the forepart of a shoe positioned in the press and, as explained, are 35 hinged at their forward ends about the lower end of post 36 in order that they may be opened and closed with respect to the shoe. These platens are prevented from dropping off the lower end of post 36 by means of a resilient retaining 40 clip 40 which is anchored to the platen 39 and engages over a flange 41 which is fixedly located on post 36. An additional post 42 extends slidably through slots 31 of arms 28 and 29 and has 45 its lower end terminating in a pin portion 43 which extends rotatably within a suitable opening provided therefor adjacent the free or rearward end of platen 39. This end of the platen is prevented from dropping off pin portion 43 by 50 means of a spring clip 44 which is anchored to the platen and seats over a flange 45 that is fixedly attached to the post 42. A similar post 46 slidably extends through the slots 35 in the swingable arms 32 and 33 located at the other side of the support 18 and has a downwardly extending pin portion 47 rotatably located in a suitable opening adjacent the rearward end of platen 38. A resilient clip 48 serves to keep this 55 platen from dropping off pin portion 47 by seating over a flange 49 that is fixed with respect to the post 46.

60 A compression spring 50 surrounds the lower end of forward post 36 and reacts between such post and a washer 51 which spans slot 23 and bears against the under side of support 18. The wing post 42 is similarly provided with a compression spring 52 reacting between the post and a washer 53 which spans the slot 31 of arm 29 and bears against the latter. A spring 54 similarly reacts between post 46 and a washer 55 that

bears against the under side of arm 33. By virtue of this arrangement the platens 38 and 39 are given a normal bias downwardly toward the pressure applying pad 14 in order that they may yield upwardly if required. Undue downward movement of the posts 36, 42 and 46 with respect to the support 18 is prevented by heads 56, 57 and 58, respectively located adjacent their upper ends.

65 The upper ends of wing posts 42 and 46 are connected by a tension spring 59 which gives these posts a normal bias toward each other.

Near its forward or wider end the slot 26 in wing 24 is provided with a recess or shoulder 60 which accommodates post 46. All three platen 15 support posts are slidable longitudinally along their respective confining slots 23, 31 and 35 and the wing posts 42 and 46 in addition are movable laterally within the confining limits of segmental slots 26 and 27. The platen 38 may be maintained 20 in open position by sliding post 46 forwardly into the recess 60 where it will be held by tension of spring 59 until moved by the operator.

In operation the platens are held open in the manner just described with post 46 being located 25 in recess 60. A shoe is then positioned on the press beneath toe post 12 and heel post 13 with its sole engaging above pressure pad 14. The operator then moves post 46 within recess 60 so as to permit the platens 38 and 39 to engage 30 about the forepart of the shoe, at the same time guiding them into the welt crease so that they bear in supporting relation above the welt extension of the sole. The press is then inflated, thus exerting pressure against the bottom of the 35 shoe which is counteracted in the welt extension area by platens 38 and 39. If the nature of the applied pressure should warrant it, these platens are yieldable upwardly by virtue of their resilient 40 mounting. When shoes of markedly different sizes from those previously handled are to be operated on, welt crease platens of different sizes may be readily substituted by simply unhooking 45 clips 40, 44 and 48 from their respective post flanges and dropping the platens from the lower ends of their supporting posts. New platens equipped with similar retaining clips may then readily be applied to the supporting posts.

In Figs. 5, 6 and 7, a somewhat different form 50 of welt hold-down device is shown. Here, a press generally similar to that described in connection with the first form is provided. It has a toe post 112, to which is threaded a sleeve or collar 116 to which a support 118 is swingably attached by means of trunnions 119 and 120. The support 118 has a forwardly projecting tongue 122 slotted as at 123 to accommodate a forward post 136.

The lower end of post 136 has a pivot pin portion 137 which pivotally accommodates the forward ends of welt crease engaging platens 138 and 139, generally similar in construction to those described in connection with the first form.

60 Support 118 is provided with lateral wings 124 and 125 which are pivotally attached thereto and are adapted to be clamped in any of several desired adjusted angular positions by means of clamping bolts 61 and 62 about which the wings are respectively pivoted. These bolts are threaded into the body portion of support 118 and have winged heads which may be clamped down against the upper part of the respective wings 124 and 125 to hold them in fixed relation with support 118.

65 Wing 125 is provided with an elongate slot 127 which extends in a generally oblique direction for- 70 75

wardly and outwardly with respect to the press, and wing 124 is provided with a similar slot 126 which latter in addition has near its forward end a recess 160. A leaf spring 63 is located opposite 5 recess 160.

A post 142 extends slidably through slot 127 and has its lower end rotatably accommodated in an opening adjacent the free or rearward end of platen 139. A similar post 146 extends through 10 slot 126 and has its lower end arranged to hold the free end of platen 138. Compression springs 150, 152 and 154 respectively surround posts 136, 142 and 146 and react between the latter and suitable washers, such as that shown at 151, 15 which bear against the under side of the support 118 and its wings 124 and 125.

The operation of this form of welt hold-down device is substantially the same as that described above, except that longitudinal movement of the 20 platens and supporting posts along the press causes automatic opening and closing of the platens by virtue of the diagonal arrangement of slots 126 and 127. Platen 138 may be held in open position by sliding post 146 up into recess 160 where it is held by spring 163 subject to movement by the operator. A tension spring 159 joins the upper ends of posts 142 and 146 and tends normally to draw them together.

It will be seen that an apparatus has been provided which is well suited to fulfil its intended functions and since certain changes may be made in the above construction and different embodiments of the invention could be made without departing from the scope thereof, it is intended 30 that all matter contained in the above description or shown in the accompanying drawings shall be interpreted as illustrative and not in a limiting sense.

It is also to be understood that the following 40 claims are intended to cover all of the generic and specific features of the invention herein described, and all statements of the scope of the invention which, as a matter of language, might be said to fall therebetween.

Having described my invention, what I claim as 45 new and desire to secure by Letters Patent is:

1. A shoe press having a pressure applying pad, means including a toe post for holding a shoe thereagainst, a support on said toe post, a pair of platens pivotally joined at their forward ends and shaped to enter the welt crease of a shoe positioned in said press, and posts extending between said support and platens for holding the latter against the welt extension of a shoe, said support having laterally extending openings accommodating certain of said posts, such posts having loose motion connections with said support to allow opening and closing movement of said platens with respect thereto.

2. A shoe press having a pressure applying pad, means including a toe post for holding a shoe thereagainst, a support on said toe post, a pair of platens pivotally joined at their forward ends and shaped to enter the welt crease of a shoe positioned in said press, posts extending between said support and platens for holding the latter against the welt extension of a shoe, said support having laterally extending openings accommodating certain of said posts, such posts having loose motion connections with said support to allow opening and closing movement of said platens with respect thereto, and resilient means between said support and platens for yieldably holding the latter against said welt extension.

3. A shoe press having a pressure applying pad, means including a toe post for holding a shoe thereagainst, a pair of platens pivotally joined at their forward ends, a slotted support on said toe post, posts extending from said platens slidably through the slots in said support to permit said platens to be bodily moved with respect to said support, and spring means between said support and platens permitting yieldable approach therebetween.

4. A shoe press having a pressure applying pad, means including a toe post for holding a shoe thereagainst, a slotted support mounted on said toe post, platens shaped to enter the welt crease at the sides and toe of a shoe positioned on said press, and posts extending from said platens slidably through the slots of said support, said platens and posts being movable as a unit with respect to said slotted support along the slots thereof.

5. In a shoe apparatus having means for applying pressure to the bottom of a shoe, a welt hold-down device comprising a slotted support, platens shaped to enter the welt crease at the sides and toe of a shoe, posts extending from said platens through the slots of said support, said platens and posts being movable as a unit with respect to said slotted support, and means for holding said support above said pressure applying means.

6. In a shoe apparatus having means for applying pressure to the bottom of a shoe, a welt hold-down device comprising a support having elongate slots therein, a post extending through one of said slots, a pair of platens mutually shaped to enter the welt crease of a shoe and pivotally joined at their forward ends to the lower end of said post, additional posts extending through the remaining slots of said support and bearing against said platens, said platens and posts being movable as a unit along said support slots, and means holding said support above said pressure applying means.

7. In a shoe apparatus having means for applying pressure to the bottom of a shoe, a welt hold-down device comprising a support having elongate slots therein, a post extending through one of said slots, a pair of platens mutually shaped to enter the welt crease of a shoe and pivotally joined at their forward ends to the lower end of said post, additional posts extending through the remaining slots of said support and bearing against said platens, spring means yieldably spacing said platens from said support, said platens, posts and spring means being movable as a unit along said slots, and means holding said support above said pressure applying means.

8. In a shoe apparatus having means for applying pressure to the bottom of a shoe, a welt hold-down device comprising a support having a forwardly disposed longitudinally extending elongate slot and a pair of rearwardly disposed laterally opposed oblique slots, a post extending through said forward slot, a pair of platens mutually shaped to enter the welt crease of a shoe and pivotally joined at their forward ends to the lower end of said post, additional posts extending through each of said oblique slots and respectively connected at their lower ends to the free end of each of said platens, whereby longitudinal movement of said platens and posts effects opening and closing movement of the platens, and means for holding said support above said pressure applying means.

9. In a shoe apparatus having means for applying pressure to the bottom of a shoe, a welt

hold-down device comprising a support having a forwardly disposed longitudinally extending elongate slot and a pair of rearwardly disposed laterally opposed oblique slots, a post extending through said forward slot, a pair of platens mutually shaped to enter the welt crease of a shoe and pivotally joined at their forward ends to the lower end of said post, additional posts extending through each of said oblique slots and respectively connected at their lower ends to the free end of each of said platens, whereby longitudinal movement of said platens and posts effects opening and closing movement of the platens, means for altering the angularity of said oblique slots, and means for holding said support above said pressure applying means.

10. In a shoe apparatus having means for applying pressure to the bottom of a shoe, a welt hold-down device comprising a support having a forwardly disposed longitudinally extending elongate slot, a slotted arm pivotally mounted at each side of said support rearwardly of said forward slot, a post extending through said forward slot, a pair of platens mutually shaped to enter the welt crease of a shoe and pivotally joined at their forward ends to the lower end of said post, additional posts extending through said slotted arms and respectively connected at their lower ends to the free ends of each of said platens, and means for holding said support above said pressure applying means.

11. In a shoe apparatus having means for applying pressure to the bottom of a shoe, a welt hold-down device comprising a support having a forwardly disposed longitudinally extending elongate slot, a slotted arm pivotally mounted at each side of said support rearwardly of said forward slot, a post extending through said forward slot, a pair of platens mutually shaped to enter the welt crease of a shoe and pivotally joined at their forward ends to the lower end of said post, additional posts extending through said slotted arms and respectively connected at their lower ends to the free ends of each of said platens, and means for holding said support above said pressure applying means.

12. In a shoe apparatus having means for applying pressure to the bottom of a shoe, a welt hold-down device comprising a support having a forwardly disposed longitudinally extending elongate slot and having laterally disposed openings located rearwardly of said slot, slotted arms swingably pivoted to said support so as to span said openings, a post extending through said forward slot, a pair of platens mutually shaped to enter the welt crease of a shoe and pivotally joined at their forward ends to the lower end of said post, additional posts extending through said slotted arms and respectively connected at their lower ends to each of said platens, and means for holding said support above said pressure applying means.

13. In a shoe apparatus having means for applying pressure to the bottom of a shoe, a welt

hold-down device comprising a support having a forwardly disposed longitudinally extending elongate slot and having laterally disposed openings located rearwardly of said slot, slotted arms swingably pivoted to said support so as to span said openings, a post extending through said forward slot, a pair of platens mutually shaped to enter the welt groove of a shoe and pivotally joined at their forward ends to the lower end of said post, additional posts extending through said slotted arms and respectively connected at their lower ends to each of said platens, spring means connecting said additional posts tending normally to close said platens, spring means between said support and platens urging the latter downwardly, and means for holding said support above said pressure applying means.

14. In combination with a shoe press comprising a pad box, a bow member carried by and extending longitudinally over said pad box, a pressure applying pad on said pad box, a toe post and a heel post carried by said bow member for holding a shoe against said pad, said toe-post being supported in fixed relation to the pad box; a welt hold-down unit comprising platens pivotally joined at their toe ends and shaped to enter the welt crease of a shoe positioned in said press, and means resiliently mounting said platens on said toe post, said means being arranged to permit opening and closing of said platens about their pivotal joint.

15. In combination with a shoe press comprising a base, a bow member carried by and extending longitudinally over said base, a pressure applying pad on said base, and means including a threaded toe post screwed into said bow member for holding a shoe against said pad; a welt hold-down unit comprising pivotally joined platens shaped to enter the welt crease of a shoe positioned in said press, a support including an internally threaded sleeve screwed on said toe post for vertical adjusting movement therealong, and means resiliently mounting said platens on said support.

16. A shoe press having a pressure applying pad, means including a toe post for holding a shoe thereagainst, a support mounted on said toe post, a pair of platens pivotally joined at their forward ends and shaped to enter the welt crease of a shoe positioned in said press, and posts mounting said platens on said support, said posts having loose motion connections with said support providing for opening and closing movement of said platens about their pivotal joint and for longitudinal movement of said platens with respect to said support.

17. In a sole attaching apparatus, a pressure pad, a cradle sustained above the pad for limited longitudinal swinging movement about an axis spaced a considerable distance above the pad and extending transversely thereof, a welt hold-down suspended from the cradle and positioned near the pad, and springs interposed between the hold-down and the cradle to permit the hold-down to yield upward toward the cradle.

WILLIAM C. CARD, JR. 65
